UNITED STATES PATENT OFFICE

161,484

POLISHING MACHINE

Curtis Y. McQuown, Chicago, Ill.

Application April 5, 1949, Serial No. 1,802

Term of patent 3½ years

(Cl. D9—2)

To all whom it may concern:

Be it known that I, Curtis Y. McQuown, a citizen of the United States, residing at Chicago, in the county of Cook, State of Illinois, have invented a new, original, and ornamental Design for a Polishing Machine, of which the following is a specification, reference being had to the accompanying drawing, forming part thereof, in which:

Fig. 1 is a side elevational view of a polishing machine showing my new design;

Fig. 2 is a front elevational view thereof;

Fig. 3 is a rear elevational view thereof; and

Fig. 4 is a top plan view thereof.

The bottom of the machine is plain and unornamented.

I claim:

The ornamental design for a polishing machine, as shown and described.

CURTIS Y. MCQUOWN.
